UNITED STATES PATENT OFFICE.

DAVID M. WATSON, OF MCKINLEY, PENNSYLVANIA.

LID SUPPORT.

Application filed January 25, 1923. Serial No. 614,733.

To all whom it may concern:

Be it known that I, DAVID M. WATSON, a citizen of the United States, residing at McKinley, in the county of Montgomery and State of Pennsylvania, have invented certain new and useful Improvements in Lid Supports, of which the following is a specification.

My invention relates to a lid support 10 adapted for use on cabinets, chests, desks or like objects having a hinged member. The object is to provide a support of a simple construction which will automatically fall into a supporting position when the lid is 15 raised and which will be automatically released from its supporting position by a continued raising of the lid and permit it to be lowered.

This object, and other advantageous ends 20 which will be described hereinafter, I attain in the following manner, reference being had to the accompanying drawings in which—

Figure 1 is an elevation, partly in section, 25 of a cabinet having my invention applied thereto,

Figure 2 an enlarged view of Figure 1 illustrating my invention in a supporting position,

Figure 3 a section on line 3—3 of Figure 1, and

Figure 4 a fragmentary perspective view of the support.

I have illustrated my lid support as applied to a phonograph cabinet. Referring to the drawings, 1 designates the body of the cabinet and 2 the lid. My support 3 is pivoted to the lid at 4 and includes a slot 5 terminating in an oblong opening 6. An oblong guide block 7, smaller than opening 6, is disposed therein in such manner as to leave a continuous space, or guideway, 8 between the wall of the opening and the periphery of the block. A pin 9 is secured to the body of the cabinet and the supporting member is so mounted that slot 5 and guideway 8 may slide thereon. A lateral projection 10 on the side wall of the opening and a notch 11 in the guide form an offset 12 in the guideway which serves to limit the raising of the lid and support it in raised position. A strip spring 13 closes the entrance to the upper run 14 of the guideway and deflects pin 9 into the lower run

15 when raising the lid. Any suitable 65 means may be provided to hold the guide in position preferably a casing 16 having depressions 17 through which are passed screws or other securing means for the guide. The casing may be secured to the 70 support in any suitable manner.

When the lid is closed, pin 9 will be in the upper end of slot 5. Raising the lid will cause the slot to travel upwardly relatively to pin 9 until it engages spring 13 75 which will cause the lower run 15 of guideway 8 to travel on the pin until the pin abuts projection 10 which acts as a stop for the raising of the lid so that support 3 will swing by gravity until notch 11 engages pin 80 9. The support is thus automatically swung into a supporting position. To lower the lid it is first raised until pin 9 engages a point 16, at the end of lower run 15 of the support, which limits the raising movement. 85 Gravity will have a tendency to swing the support and cause the upper run 14 of guideway 8 to travel on pin 9. The lid is then lowered. During this movement, upper run 14 of the guideway will slide on pin 9 until it engages strip spring 13 which, due to its flexibility and free movement, permits the pin to pass out of run 14 into slot 5.

By constructing a support in this manner, 85 the support will swing by gravity into the supporting position and from the supporting position to permit lowering of the lid.

While I have described my invention as taking a particular form, it will be understood that the various parts of my invention may be changed without departing from the spirit thereof, and hence I do not limit myself to the precise construction set forth, but consider that I am at liberty to 95 make such changes and alterations as fairly come within the scope of the appended claims.

Having thus described my invention, what I claim as new and desire to secure by Letters Patent is:—

1. The combination with a cabinet or other object having a lid and a fixed pin, of a supporting rm pivoted to the lid and having a slot terminating in a continuous 105 guideway having an offset in its lower run, the slot and guideway being adapted to slide on the pin, and a strip spring adapted

to deflect the pin from the slot into the lower run of the guideway and permit it to pass from the upper run into the slot.

2. The combination with a cabinet or 5 other object having a lid and a fixed pin, of an arm pivoted to the lid and having a slot terminating into an opening; a lateral projection on the side wall of the opening; a guide block having a notch, mounted in 10 the opening and spaced therefrom with the notch adjacent the projection to provide a continuous guideway around the block, the slot and guideway being adapted to slide on the pin; a strip spring secured to the 15 guide for deflecting the pin into the lower run of the guideway and permitting it to pass out of the upper run, and a casing 20 and means for holding the guide in position.

3. The combination with a cabinet or 20 other object having a lid and a fixed pin,

of an arm pivoted to the lid and having a slot terminating into an opening; a lateral projection on the side wall of the opening; a guide block having a notch, mounted in 25 the opening and spaced therefrom with the notch adjacent the projection to provide a continuous guideway around the block, the slot and guideway being adapted to slide on the pin; a strip spring secured to the 30 guide for deflecting the pin into the lower run of the guideway and permitting it to pass out of the upper run, and a casing for holding the guide in position.

In testimony whereof I have signed my name to this specification in the presence of 35 two subscribing witnesses.

DAVID M. WATSON.
